Primary Examiner — Susan Moon Lee(74) *Attorney, Agent, or Firm* — NSIP Law(57) **CLAIM**

The ornamental design for a digital clipboard reader, as shown and described.

DESCRIPTION

FIG. 1 is a front perspective view of a digital clipboard reader; FIG. 2 is a front view of the digital clipboard reader of FIG. 1; FIG. 3 is a rear view of the digital clipboard reader of FIG. 1; FIG. 4 is a left-side view of the digital clipboard reader of FIG. 1; FIG. 5 is a right-side view of the digital clipboard reader of FIG. 1; FIG. 6 is a top plan view of the digital clipboard reader of FIG. 1; FIG. 7 is a bottom plan view of the digital clipboard reader of FIG. 1; and, FIG. 8 is a rear perspective view of the digital clipboard reader of FIG. 1. Features shown in broken lines in FIGS. 1, 2, 3, 5, 6, and 8 form no part of the claimed design.
